PAVING APPARATUS AND METHOD

William Mayo Venable, Pittsburgh, Pa., assignor
to Blaw-Knox Company, Pittsburgh, Pa., a cor-
poration of New Jersey

Application January 24, 1936, Serial No. 60,615

24 Claims. (Cl. 94—45)

This invention relates to paving and particularly to a method and apparatus for finishing roadways formed of initially plastic material such as concrete.

5 In the construction of roadways of concrete, for example, a "sub-grade" is first prepared and freshly mixed concrete deposited thereon between "road rails" or forms defining the edges of the slab to be formed. Various types of apparatus for finishing the surface of the concrete slab have been proposed heretofore, to avoid the hand finishing which was employed in the early days of concrete road construction. A common 10 feature of finishing machines in general use is a screed, the ends of which rest upon the road rails. Each screed has a front surface to push forward surplus concrete, and a bottom surface to work upon the upper surface of the concrete slab. Screeds are reciprocated longitudinally 15 while being moved forward, pushing surplus concrete in front of them, the weight of which surplus concrete tends to compact the other concrete as the screed works upon it. Some finishing machines are also provided with tampers of 20 various sorts and more recently with vibrators, the object of the latter being to facilitate the working of concrete having a low plasticity, by reason of the amount of aggregate in the mixture. 25

30 It has long been recognized that road finishing machines now available are not capable of working concrete of as low plasticity (i. e. containing as little water or as much aggregate) as is utilized in massive masonry construction, and 35 obtaining the desired compacting of the concrete. Certain road finishing machines, e. g. as shown in my prior Patent No. 1,887,341, are capable of working concrete of a somewhat reduced plasticity but even a machine of the type 40 shown in the patent requires that the concrete be sufficiently plastic to permit two successive screenings. The usual practice in operating screening machines has been to move the machine over the work more than once, leaving a 45 comparatively smooth but a slightly high surface the first time and then removing the surplus height by subsequent passes.

Such machines are objectionable not only because the necessity for two passes limits the use 50 thereof to concrete having relatively high plasticity but also because it is practically impossible to obtain a slab of uniform thickness.

Concrete as deposited in front of the machine is not perfectly distributed over the width of the 55 road and as the machine advances the height of

the concrete pile pushed forward in front of the screed varies from point to point along the screed. Consequently, even if the concrete be of uniform consistency, the amount which flows beneath the screed varies from point to point, 5 and the concrete left after each pass is neither perfectly graded nor uniformly compacted. Variations in plasticity increase the unevenness, as they occasion unequal settling after the finishing machine has completed its work, some settling 10 being unavoidable with the mixtures such machines are capable of placing.

It is obviously impossible, with machines such as known heretofore, to work concrete having a minimum of water per unit of other components. Such machines are practically limited to concrete having a plasticity such that it gives a slump of more than 1½". The object of my invention is to provide a method and apparatus 15 capable of finishing concrete having a maximum 20 of aggregate and a minimum of water, to the desired degree of smoothness, in a single pass.

In accordance with my invention I eliminate entirely the reciprocating screed as a means for conditioning, compacting or smoothing the concrete. 25 In a traveling unit including a wheeled frame adapted to move on road rails, I provide vertically oscillating tampers both to push forward surplus concrete and to condition and pack concrete in place against a moving steadily forward form, which prevents all uplift of concrete behind the tampers. This form is supported by the wheeled frame. The unit carries sources of motive power for driving it and the reciprocable tampers. A wide range of adjustment of the tampers and form is obtainable with my construction and numerous other features 30 and advantages thereof will appear as the detailed description proceeds, the novel features 35 being pointed out specifically in the appended 40 claims.

A present preferred embodiment of the invention is illustrated in the accompanying drawings although it will be understood that it may be 45 otherwise embodied or practiced in the scope of my broader claims. In the drawings:

Figure 1 is a plan view of the apparatus;

Figure 2 is a sectional view taken along the line II—II of Figure 1 with parts broken away; 50

Figure 3 is a side elevation;

Figure 4 is a view partly in section along the line IV—IV of Figure 1;

Figure 5 is a partial side elevation of the structure shown in Figure 4;

Figure 6 is a partial plan view of a modified construction;

Figure 7 is a side elevation thereof;

Figure 8 is a sectional view taken substantially along the line VIII—VIII of Figure 7;

Figure 9 is a partial front elevation of a modified tamper;

Figure 10 is an end elevation with parts in section;

Figure 11 is a diagrammatic view of the behavior of the concrete in front of the advancing tampers;

Figure 12 is a vertical sectional view through a modified form of tamper showing the tamper oscillating mechanism in greater detail; and

Figure 13 is a partial elevation of a tamper showing a detail.

To facilitate an explanation of the apparatus of my invention, the description thereof will be divided into sections each referring particularly to one portion of the apparatus as follows:

1. The car and its drive.

2. The form and its adjustable supporting means.

3. The tampers and their reciprocating mechanism.

4. The side wings or guides.

5. Modified forms and other details.

The car and its drive

Referring particularly to Figures 1 through 5 for the present, the apparatus of my invention comprises a frame 10 having front and rear channels 11 and 12 and side members composed of spaced channels 13. The side members are secured to the front and rear members in any convenient manner, as by welding. Bearing brackets 14 extend downwardly from the side members adjacent the front and rear channels. Shafts 15 journaled in bearings provided by the brackets carry wheels 16 adapted to roll on road rails 17 which serve as the forms for the slab to be finished. The shafts 15 are provided with sprockets 18 so that the wheels 16 may be operated by a chain drive from a power source on the car, specifically, the internal combustion engine 19.

Auxiliary side channels 20 are supported on the channels 13. Transverse channels 21 are supported on the channels 20. A longitudinal channel 22 has its rear end disposed on the upper flange of channel 12 and its forward end secured to the lower flanges of channels 21. The engine 19 is supported on the channel 22 and on the inner channel 20 on the right hand side of the frame as shown in Figure 1. Integral with the engine is a speed reduction gear and clutch 23, and a clutch operating lever 24. The slow speed shaft of the speed reduction gear 23 is shown at 25 and is connected by a chain and sprocket drive to a shaft 26 mounted in a gear box 27. The gear box 27 is supported on transverse channels 28 and 29. The lefthand ends of the channels are secured to one of two longitudinal channels 30 mounted similarly to the channel 22. The righthand end of the channel 29 is secured to the channel 22 and the righthand end of the channel 28 to a longitudinal channel 31 extending between and supported by the channel 12 and the channel 29. The gear box 27 is provided with a shaft 32 having a sprocket and gear loose thereon and a jaw clutch 33 by which either the sprocket or the gear may be secured to the shaft. Thus the shaft 32 may be driven from the shaft 27 alternately by the gear drive 34 or the chain and sprocket

drive 35. The two drives are adapted to turn the shaft 32 in opposite directions. An actuating lever 33a is provided for the clutch member 33.

Similar transverse driving shafts 36 are journaled in bearings 37 and 38. The bearings 37 are supported on longitudinal members 39 extending between the channel 12 and the channel 28. The bearings 38 are supported on the channels 20 resting on the side channels 13. A jaw clutch 40 is disposed between the shafts 36 and includes a member 41 fixed relative to but rotatable on the shafts 36 and cooperating members 42 movable along the shafts 36 but non-rotatable relative thereto. By means of suitable operating levers, either or both of the shafts 36 may be driven from the shaft 32 by the chain and sprocket drive 43 connecting the shaft 32 and the fixed member 41 of the clutch 40.

The shafts 36 are provided at their outer ends with driving sprockets 44. These sprockets cooperate with chains 45 trained over the sprockets 18 and suitable idler sprockets 46 journaled between the side channels 13, to drive the wheels 16. This arrangement of driving connections makes it possible to drive all four wheels in either direction, or only the wheels on one side of the car. This latter is of advantage in working on curves.

The form

The form comprises a generally flat sheet or plate 50 having its leading edge flanged upward and provided with transverse stiffening channels 51. The plate 50 is also provided with longitudinal stiffening channels 52. The form is supported on a frame movable relative to the car frame 11, 12, 13 and composed of longitudinal channels 53 and transverse channels 54 secured to the lower flanges of the channels 53. The form plate 50 is suspended from the transverse channels 54 by hanger bolts 55 which are slidable through aligned holes in the flanges of the channels. The bolts 55 are secured to the plate 50 head downwardly by yokes 56 welded or otherwise secured to the channels 51. The bolts 55 are threaded through nuts 57 welded to the upper flanges of the channels 54. Nuts 58 are welded to the extreme upper ends of the bolts 55. By applying a wrench to the nuts 58, the various bolts 55 may be adjusted to give the form plate 50 the desired contour. The channels 51 permit slight bending of the form as a result of the adjustment of the bolts 55.

The outer edges of the form plate 50 are held in engagement with the road rails 17 by the hold-down bolts 59 which pass through aligned holes in the channels 54 in the same manner as the bolts 55. The bolts 59 are provided with coil springs 60 compressed between the lower flanges of the channels 54, and washers 61 and nuts 62 threaded on the bolts 59. Check nuts 63 are threaded on the upper ends of the bolts 59 to limit downward movement of the edges of the form.

Spaced channels 64 extend transversely of the car frame ahead of the channels 51. The ends of the channels 64, however, are not secured to the side channels 13 of the car frame but merely rest thereon. The upper flanges of the longitudinal channels 53 are secured to the lower flanges of the transverse channels 64. By raising and lowering the channels 64, however, the form plate 50 may be adjusted vertically. The upward movement of the form frame composed of the channels 53 and 54 is limited by the engagement of the upper flanges of the channels 54 with the lower flanges 75

of the channels 13. Independent means are provided for raising and lowering opposite sides of the form frame. A description of one of the adjusting means will therefore suffice for both.

5 Short channels 65 extending between channels 21 provide bearings 66 for a short transverse shaft 67. Between the two outer bearings, the shaft 67 is provided with a worm wheel 68. A worm 69 on a vertical shaft 70 is in mesh with the worm 10 wheel 68. The shaft 70 is journaled in a bearing carried on plate 71 extending between the channels 21 and a thrust bearing 72 carried on a plate extending between the channels 13. The shaft 15 70 is provided with a hand wheel 73.

15 The shaft 67 is also provided with an eccentric 74 between the two inner bearings 66. A link 75 connects the eccentric 74 and one of the longitudinal channels 53. On rotation of the hand wheel 73, therefore, the shaft 67 turns and the 20 resulting rotation of the eccentric 74 raises the link 75 and one side of the form frame.

Vertical movement of the form frame in the car frame is guided by dowel pins 76. The dowel pins 76 pass through aligned openings in plates 25 77 secured to the upper and lower flanges of the channels 53 and similar aligned openings in plates 78 secured to the upper and lower flanges of channels 13.

The form frame comprising the channels 53 and 30 54 is shown in Figures 2 and 3 in its lowermost position. The upward movement of the frame, as before stated, is limited by engagement of the frame flanges of the channels 54 with the lower flanges of the channels 13. Downward movement 35 of the rear end of the form frame is limited by plates 79 secured to the upper flanges of the channels 53 and over-lapping the lower flanges of the channels 20.

Upward pressure of the concrete on the form 40 plate is transmitted directly to the channels 54, the channels 53 and then through the links 75 and eccentric 74 to the channels 21 which are firmly secured to the car frame comprising the channels 11 and 13. The entire weight of the apparatus is thus effective to resist the upward pressure of the 45 concrete. While the frames of the car and form are relatively rigid, they may be so designed as to permit slight warping so that all the wheels 16 will have contact with the road rails 17, even though the latter are not precisely horizontal or 50 parallel. This is highly desirable because the traction of the driving wheels on the road rails is the only force to overcome the friction between the form and the concrete being finished, which 55 may amount to several thousand pounds. In order to transmit force to overcome this friction directly from the car frame to the form, I provide bracket plates 80 extending downwardly from the inner channels 13 of the side members of the car frame. Struts 81 are pivoted to the lower 60 ends of the plates 80 and to the form adjacent its leading edge as shown at 82. The pivotal connection between the struts 81, the bracket plates 80 and the form permit the latter to be raised and lowered relative to the car frame as already 65 described. The bracket plates 80 sustain the horizontal thrust necessary to force the form over the slab and the channels 54 need, therefore, only be rigid enough to withstand the bending moment developed by the upward pressure of the 70 concrete.

The tampers and their reciprocating mechanism

The form which has been described in detail 75 does not operate in the manner of a screed to

push concrete in front of it but serves only to prevent upflow of the concrete already in place. Tampers are disposed immediately ahead of the form whereby the concrete is agitated into its most plastic condition as the leading edge of 5 the form passes over it. The tampers also pack the concrete firmly under the form and between the road rails. The length of the form is such that concrete cannot flow under it as a result of the agitation produced by the tampers. As a 10 matter of fact, the form is of such length that the concrete is quite solid at the trailing edge, being preferably firm enough to support the weight of a man without denting. The concrete is plastic only for a short distance back of 15 the leading edge of the form.

Tampers 85 are disposed end to end and are supported from the channels 64 for oscillation. The tampers are of box-like construction having closed bottoms, and reenforcing webs 86 between 20 the front and rear walls. The forward lower edge of each tamper is rounded.

Each tamper has at least one pair of spring suspensions 87 for supporting it from the channels 64. Each of these suspensions comprises a 25 rod 88 the lower end of which is loosely secured to a bracket 88' fixed in the structure of the box forming the tamper, by any convenient means such as a pin and slot connection. The rod 88 passes through a hole in a plate 89 secured to the 30 channels 64. Springs 90 and 91 on the rod 88 are compressed between the plate 89 and washers 92 backed up by nuts 93 whereby the tamper itself is resiliently supported on the channels 64.

As shown in Figure 3, the tampers extend upwardly between the channels 64 and are provided with brackets 94 whereon is mounted mechanism 95 for vibrating or oscillating the tamper. This mechanism, as shown in Figure 12, consists of a housing 96 secured to the brackets 94, having a shaft 97 journaled therein in suitable bearings, and an eccentric weight 98 secured to the shaft. Vibrating mechanism of this type is more fully described and claimed in the copending application of Harold E. McCrery Serial No. 704,396. 40 It will be apparent, however, that rotation of the shaft 97 will cause vibration of the tamper 85 by reason of the eccentric mounting of the weight 98. The eccentricity of the weight is adjustable. The oscillating mechanisms 95 are driven through extensible shafts 99 connected thereto and to driving shafts by universal joints 100. The driving shafts are shown at 101, being journaled in suitable bearings 102 carried by the channels 21. Power is supplied to the shafts 101 from 50 any convenient source such as an internal combustion engine 103 mounted on channels 30. The engine has an integral clutch and operating shaft 104 therefor. The engine is coupled to an intermediate shaft 105 journaled in bearings supported in the same manner as those shown at 55 102. Chain and sprocket drives 106 connect the shaft 105 with the two adjacent shafts 101. A supplementary chain and sprocket drive 107 connects the third shaft 101 to one of those directly 60 connected to the shaft 105. The speed of the engine may be varied by the usual means, to produce the desired agitation or conditioning of the concrete.

The rear walls of the tampers bear on a back up 70 plate 108 carried at the leading edge of the form 50. The tampers being confined between the plate 108 and the concrete piled up in front of them, as shown in Figure 11, reciprocate vertically. Sufficient clearance between adjacent 75

tampers and between the tampers and the road rails is provided so that it is not necessary that the tampers operate in synchronism.

Figure 11 indicates diagrammatically the manner in which the concrete piles up in front of the tampers. The dotted line 109 indicates the outline of the mass of concrete pushed ahead of the tampers in normal operation. Due to the rapid vibration of the tampers, the concrete between the tampers and dotted line 110 is made semi-fluid, in which condition it will readily flow under the form 50. If the speed of forward movement of the machine is reduced, concrete will be made fluid within the zone indicated by the dotted line 111. Conversely, if the speed of the machine is increased the zone will approach the tampers as indicated by the dotted line 112. The degree of agitation is preferably so controlled that the concrete under the form is plastic back approximately as far as the dotted line 113 and no farther. By utilizing the provisions for varying the speed or amplitude of vibration imparted to the tampers, the machine may be adapted for handling concrete of various degrees of plasticity. Normally the vibrations of the tamper are rather small in amplitude, say between $\frac{1}{8}$ " and $\frac{3}{8}$ ". The normal position of the tampers relative to the form may be controlled by adjusting the nuts 93, and the inclination of their bottoms to the horizontal changed to suit various slab contours. Ordinarily the bottoms of the tampers should be at about the same level as the bottom of the form.

The side wings or guides

35 Side guides 115 are carried in front of the machine frame, the forward edges being notched to receive the rails 17 on which the guides slide. At their rear edges, the guides have pins 116 slideable in slots in brackets 117 which support the guides against outward thrust as shown in Figures 1 and 2. The guides extend inwardly of the inner bearing brackets supporting the wheels 16. When not in use, the guides may be raised by operating levers 118 secured to shafts carrying eccentrics 119. Links 120 connect the eccentrics to the guides.

Modified forms and other details

Figures 6, 7, and 8 show a modified form of tamper 120 which extends substantially the full width between the road rails 17. The tamper 120 is otherwise similar to the tamper 85. It is carried on spring suspensions 121. Each suspension 121 includes a yoke 122 carried on the channels 64. A plate 124 extending across the top of the tamper has bolts 125 welded to the lower side thereof which extend downwardly through holes in the bottom inturned portions of the yoke 122. Supporting springs 126 are compressed between the inturned bottom portions of the yoke and washers 127 backed up by nuts 128. Springs 129 are compressed between the plate 124 and washers welded to the lower ends of bolts 125a threaded through tapped holes in the yoke 122 and extending downwardly therefrom in line with the bolts 125.

Vibrating mechanisms 130 similar to those shown in 95, are mounted on the plates 124 carried by the tamper and are coupled to an intermediate drive shaft 131 journaled in bearings 132 supported on the cross plates extending between the channels 64. The shaft 131 is connected to the mechanisms 130 through extensible shafts and universal joints as described in connection with the modification of Figures 1 through 3.

Since the two vibrating mechanisms 130 are mounted on the same tamper, they should be operated in synchronism to avoid excessive stress in the tamper. The shaft 131 is driven through a belt drive 133 and another intermediate shaft 5 134 by an engine 135, corresponding to the engine 103 mounted somewhat differently. The remaining details of the structure of Figures 6 through 8 correspond to those of the modification of Figures 1 through 3 with one exception, 10 viz., that the form 50' and the tamper 120 (see Figure 7) are provided with groove casting ribs 136 and 137. These ribs are secured to the tamper and form in any convenient manner, for instance, by lugs 138 extending upwardly through slots in 15 the tamper and form, and wedges 139 extending through the lugs. By this means, it is possible to form a continuous groove extending along the slab, where such is desired.

Figures 9 and 10 show a further form of tamper 20 having a bottom plate 140 adapted to traverse the sub-grade. The plate 140 is supported by edgewise plates 141 extending upwardly therefrom. The tamper is completed by front and rear walls 141a and 141b. This type of tamper, however, is limited to pavement having no reenforcing steel or other inclusions which would prevent it from passing through the concrete.

Figure 12 illustrates in addition to the details of the operating mechanism 95, a further modified 30 form of tamper 142. This tamper is composed of flat and bent plates assembled and secured together in the manner shown.

Road finishing machines often have provisions permitting them to be adjusted for various road 35 gauges. While such means have not been shown herein, they may be provided to accommodate changes in road width, for example, on curves, and if so, it is desirable that the concrete be subject to the action of the tampers throughout the 40 road width. Forms such as that shown at 50 may be provided in various widths depending on the adjustment provided for the supporting wheels. Figure 13 illustrates means by which the tamping effect can be obtained throughout the road width 45 where the latter is greater than the total width of the tampers 85. As shown in Figure 13, the tampers 85 nearest the road rails 17 are provided with extensions 145. These extensions are preferably of hollow box form and have a rounded 50 front lower edge. The extensions may be secured to the tampers 85 by bolts 146. The extensions 145 must clear the tops of the rails 17 and as the bottoms of the tampers 85 normally are below the tops of the rails, the relative positions of the tampers and extensions are as shown in Figure 13. The extensions oscillate with the tampers, however, and ensure proper agitation or conditioning 55 of the concrete between, the ends of the tampers 85 and the rails 17. The form 50 serves to hold 60 the concrete in position after tamping, in the manner already described, until it becomes non-plastic.

It will be apparent from the foregoing description that the invention is characterized by numerous advantages over finishing machines previously known, in that it makes possible the finishing of a concrete slab, for example, in a single pass, to a true surface, using concrete having less plasticity, (that is, having more aggregate or less 70 water) than it has been possible to finish with machines of other types. The invention makes possible for the first time the satisfactory finishing of the upper surface of a flat slab formed of concrete having a low plasticity.

In contrast to the effect of the screed of an ordinary finishing machine, the form 50 exerts no smoothing or troweling action whatever, such as is exerted by a plasterer in smoothing a wall surface. It is merely a sliding form. The concrete is packed against it when placed and each particle retains exactly the same position that it occupies when first placed against the form, except insofar as it is agitated by the tamper in front of the form until the machine is moved forward sufficiently far to prevent such agitation from being effective.

The construction is such that practically no vibration is communicated by the tamping device to the form itself. Any agitation that is communicated to the form is transmitted through the concrete. The form must not be considered as a member to work upon the concrete but merely as a member to hold the concrete in place.

20 The invention avoids the difficulty inherent in the use of a reciprocating screed and operates to compact as well as shape the concrete in a single pass. This is what makes it possible to reduce the amount of water or increase the 25 amount of aggregate in the concrete. By avoiding a reciprocating screed, transverse forces on the road rails are eliminated. Such forces are the cause of rail settlement and mis-alignment. Reciprocating screed machines, furthermore, are 30 limited to crowns which are circular arcs, as they will not function satisfactorily on other types of curves. This limitation is avoided by the present invention. The casting of longitudinal grooves is facilitated and eliminates the necessity of cutting such grooves after finishing.

35 Since the invention makes it possible to finish a slab in one pass leaving the slab less plastic than has heretofore been possible, cements characterized by quick setting may be employed. The 40 advantage of such cements is obvious.

45 Another advantage of the invention is that it does not interfere with the present methods of placing concrete, reinforcing steel, or expansion joints.

45 The entire weight of the apparatus is available to increase the traction of the driving wheels along the road rails.

The form may be adjusted to a variety of contours or crowns and one side may be raised or lowered independently of the other. Although 50 the form engages the road rails, it is supported from the car, reducing friction between the form and the rails. The form is carried directly on the car and the upward pressure of the concrete in the slab is transmitted directly to rigid 55 sustaining members.

In the operation of the apparatus, the concrete being finished is rendered plastic for only a short distance behind the leading edge of the 60 form and the slab is firm enough to support a man's weight after the form has passed over it. Machines known previously require concrete so plastic that it will not support a man from 50 to 300 feet behind the machine.

65 The spring supports for the tampers prevent noisy operation but the springs are not materially stressed because of the small amplitude of the vibrations. Since each tamper has two independent suspensions, the opposite ends may be 70 adjusted to different levels.

The machine is also capable of being used effectively to place concrete of the plasticity hitherto in common use, or to compact and spread such road materials as gravel or crushed stone.

75 Although I have illustrated and described

herein only a preferred practice and form of my invention, it will be understood that the invention may be practiced and embodied otherwise than as shown without departing from the spirit thereof or the scope of the appended claims.

5

I claim:

1. A tamper comprising a bottom plate, web plates extending upwardly therefrom in spaced relation, and means joining said web plates at 10 a level above said bottom plate.

2. In a finishing machine for road construction, a car adapted to run on road rails, members extending transversely of the car, capable of being raised or lowered with respect thereto, tampers below said transverse members, means for resiliently supporting said tampers from said members, and means for oscillating said tampers as 15 said car travels along said rails.

3. In a finishing machine for road construction, a car, parallel transverse members supported 20 on the car and capable of being raised and lowered with respect thereto, a tamper member between said transverse members, means for resiliently supporting said tamper member from said transverse members, said means being adjustable to vary the elevation of the tamper, and means for oscillating said tampers as said car 25 travels along said rails.

4. In a finishing machine for road construction, a car, parallel transverse members supported 30 on the car and capable of being raised and lowered with respect thereto, a tamper member between said transverse members, means for resiliently supporting said tamper member from said transverse members, oscillating means mounted on 35 said tamper, and means mounted above said transverse supporting members for driving said oscillating means, and means for oscillating said tampers as said car travels along said rails.

5. The process of placing concrete containing 40 so little water or so much coarse aggregate as not to be plastic under steadily applied pressure, which consists in subjecting the mass to very violent vibratory agitation immediately in front of a forwardly moving form member so as to render 45 it pseudo-fluid immediately beneath the forward form edge due to the violent agitation of its particles, holding the form down against the upward pressure of the concrete, and controlling said agitation so that said fluidity does not extend 50 to the extremity of the form farthest from the front where said agitation is applied, thereby leaving a compact non-plastic surface immediately behind said advancing form.

6. Paving apparatus comprising a car including 55 a wheeled frame adapted to traverse side rails, a tamper mounted on the frame, for vertical movement, a plate extending between said rails from a point immediately behind the tamper and adapted to serve as a form for concrete tamped 60 thereunder, and means including a rigid frame supported on the car for preventing said plate from rising under the pressure of said concrete.

7. Paving apparatus comprising a car, a tamper mounted adjacent the front of the car for 65 vertical movement, a rigid frame behind the tamper, a packing plate carried on said frame adapted to provide a surface against which concrete may be packed by said tamper, and means on said car preventing uplifting of said plate and 70 frame under the pressure applied to the concrete by the tamper.

8. In a finishing machine for concrete roads, a car, a rigid frame supported by said car and vertically adjustable with respect thereto, in 75

- combination with a tamper resiliently supported from said frame, said tamper comprising a deep trough-shaped structure with a bottom plate for acting on concrete beneath it and a front plate for pushing concrete ahead of it, rotary weights for imparting tamping motion with a vertical component at the tamper bottom, and drive mechanism for said rotary weights secured to the frame upon which the tamper is resiliently mounted.
9. In a paving apparatus, the combination with a car adapted to traverse side forms or road rails, tamping mechanism movably carried on said car, of a packing plate immediately behind said tamping mechanism, and a rigid frame mounted on the car, means for adjusting the frame vertically of the car said plate being secured to said frame and said mechanism including a vibrating tamper immediately in front of said plate having a substantially horizontal surface effective to agitate concrete into position against the underside of said plate and a substantially vertical surface effective to force surplus concrete ahead of said tamper.
10. The apparatus as defined by claim 9 characterized by means for yieldingly urging the outer edges of said plate into engagement with said rails.
11. The apparatus as defined by claim 9 characterized by means for adjusting one side of said frame vertically independently of the other end.
12. The apparatus as defined by claim 9 characterized by means for adjusting one side of said frame vertically independently of the other end, and means guiding movement of said frame relative to said car.
13. The apparatus as defined by claim 9 characterized by means extending downwardly from said car for withstanding the horizontal thrust on said plate.
14. The apparatus as defined by claim 9 characterized by said tamping mechanism including a vertically reciprocable member floatingly supported on said car, and means for vibrating said member.
15. The apparatus as defined by claim 9 characterized by side guides carried on said car ahead of said tamping mechanism and overlying said rails.
16. The apparatus as defined by claim 9 characterized by side guides carried on said car ahead of said tamping mechanism and overlying said rails, and means on the car for raising said guides out of their normal operating position.
17. Paving apparatus comprising a car adapted to travel on road rails, a form below the car supported therefrom, providing a surface against the under side of which concrete may be packed, adjustable means supporting the form at a plurality of points whereby the contour of the form may be varied, and means on the car for preventing uplift of the form without lifting the car.
18. In a paving apparatus, the combination with a car adapted to travel on road rails, of a flexible form below the car, adjustable supports for the form extending downwardly from the car, and means on the car for opposing upward thrust on the form.

19. Paving apparatus comprising a car, a vertically vibrating leveler and tamper mounted adjacent the front of the car, a packing plate immediately behind the tamper adapted to provide a surface against which concrete may be packed by said tamper, and means for rigidly securing the packing plate to the car so as to resist the upward pressure of the concrete produced by the tamper. 5

20. A method of finishing the surface of a concrete slab including the steps of depositing concrete of relatively harsh consistency between side forms, tamping the concrete locally from above until it is rendered temporarily fluid, simultaneously pushing surplus concrete ahead of the point of tamping, and confining the concrete immediately behind the point of tamping against upward flow until the temporary fluidity ceases.

21. A tamper for a concrete road finishing machine, comprising a trough shaped member of sheet metal having two substantially vertical sides of considerable depth relative to its width, a substantially horizontal bottom plate for working on concrete beneath it and a substantially vertical front plate for pushing concrete ahead of it, with bearings for a horizontal shaft firmly secured to upper portions of both of the vertical sides and a shaft in said bearings to receive power for revolving weights to actuate the tamper, said power being transmitted to said shaft by substantially horizontal mechanical driving mechanism from a power unit mounted independently of said tamper.

22. Paving apparatus comprising a car, a tamper, a spring suspension supporting the tamper from the car, and means for adjusting the spring of said suspension bodily relative to the tamper whereby the initial position of the tamper relative to the car may be varied.

23. In a road finishing machine, a car adapted to travel on side forms, a top form plate rigidly secured to said car when in operative position so as to be held down by the weight thereof and extending in a substantially horizontal plane between said side forms, a tamper immediately in front of said top form effective to condition concrete as it is being placed adjacent the leading edge thereof and force it under pressure against the under side thereof, rotary weight mechanism for actuating the tamper, means for moving the car forward at a predetermined speed, and a variable speed drive for said mechanism whereby to vary the fluidity of the material during the process of placing, due to the agitating effect of the tamper mechanism. 55

24. In a method of paving, the steps including distributing paving material between side forms, moving a top form thereover, violently tamping the material immediately in front of the top form until it is rendered temporarily fluid, applying to the top form a downward force in addition to its own weight to hold it against vertical movement under the upward pressure of said material, and maintaining engagement of said top form with the material until said material is non-plastic when uncovered by the form. 60 65
